THE NORRIS PETERS CO., PHOTO-LITHO., WASHINGTON, D. C.

UNITED STATES PATENT OFFICE.

CHRISTIAN STOLLEWERK, OF AIX-LA-CHAPELLE, GERMANY.

ORGAN.

SPECIFICATION forming part of Letters Patent No. 691,501, dated January 21, 1902.

Application filed December 28, 1900. Serial No. 41,430. (No model.)

To all whom it may concern:

Be it known that I, CHRISTIAN STOLLEWERK, music-teacher, a subject of the King of Prussia, German Emperor, residing at 49 Alfonstrasse, Aix-la-Chapelle, in the Kingdom of Prussia, Empire of Germany, have invented certain new and useful Improvements in Organs; and I do hereby declare the following to be a full, clear, and exact description of the invention, such as will enable others skilled in the art to which it appertains to make and use the same.

My present invention relates to organs, harmoniums, and other keyed wind instruments, but principally to a device with the help of which the player can make resound any combination of registers at any point of the keyboard, though his hands and feet be employed in the usual manner at play. This circumstance is of great importance, as the player is not compelled to lift his hands off the keys in order to manipulate the organ-registers, for which operation hitherto a pause was necessary.

25 In the accompanying drawings, Figure 1 is a vertical section of a keyboard provided with my invention. Fig. 2 is a rear view of the mechanism directly connected with the registers. Fig. 3 is a view of the mechanism in its lowered position. Fig. 4 is a front view of the keyboard and part of the working mechanism. Fig. 5 is a plan view of a tappet.

The parts marked 1 form part of an organ-housing and may be of any suitable construction. The keyboard 2 and its keys 3 may likewise be of any known type.

An important part of my invention is the thumb-board 4, pivotally attached to the organ-housing in posts 5 by means of the rods 6 and extending over the whole length of the keyboard, so as to be within easy reach of the thumbs of the player's hands at any point of said keyboard. Near the turning-point of the thumb-board is attached an arm or arms 7, provided with a slot in the free end surrounding a bolt 8, by means of which the thumb-board may be adjusted. Between the organ-housing and said arm 7 a spring 9 or any other device is interposed to return the thumb-board to its original position as soon as the pressure of the thumb or thumbs has

been removed. Near the upper end of the thumb-board another arm 10 is secured, and pivotally fastened to its free end is the link 11. This link is attached to a slotted lever 12, movably secured to the base 13, and carries on its under side the bent lever 14, held to the link 11 by means of the eyebolt 15 and spring 16. Against the adjusting-screw 17, with a head 18, of leather, rubber, or any other material, in the post 19, the lower end of the bent lever 14 strikes when the mechanism is lowered. (See Fig. 3.) Opposite to the slotted lever 12 are attached two posts 20, between which the short slotted lever 21 is movably arranged. In the slot 22 of this lever 21 is placed the double-armed lever 23, having a tooth 24, entering the teeth of the ratchet 25 on the drum 26. The proportions of the tooth of lever 23 and the point of the lever 14 are such that the tooth 24 catches the point of a tooth of the ratchet before the point of lever 14 leaves it. A spring 27 keeps the tooth 24 in contact with the ratchet. The posts 20 are connected by a plate 28, against which the point of the screw 29 bears, passing through an opening in the leaf-spring 30, tending to press the lever 21 against the plate 28. In the spurs of posts 20 is journaled the horizontal part of the lever 31, having a forked upper end, surrounding one of the pins 32 of drum 26. The levers 31 and 12 are connected by a rod 33, consisting of two parts having right and left thread, respectively, in order to bring the levers 31 and 12 closer together or separate them by turning the nut 34 in one direction or the other.

The base 13 is provided with bearings 35, in which the shaft 36 of the drum 26 revolves. The circumference of said drum is provided 90 with a number of laths 37, against which rest reversible tappets or keys 38, coming into contact with the pins 39 and the hooks 40 of the bars 41, hinged to the organ-housing 1.

Flush with the front of the upper part of 95 the organ-housing are suspended a number of bars 42, united at their lower extremities by a cross-bar 43, thus forming independent divisions in which are pivotally arranged the oblong boards 44, each provided with an arm 100 45. The bars 42 and cross-bar 43 are connected by means of bars 46 with a second

cross-bar 47, provided with a screw 48, for each oblong board 44. In the eye of each screw is fastened one end of either of the two sets of springs 49 or 50, and these springs keep the 5 oblong boards in the position into which they are thrown by the contact of their pin with a tappet. The hinged bars 41 are provided with an adjusting-screw 51, likewise provided with a head 52 and so adjusted that when the 10 upper end of the oblong boards 44 strike in their tilted position the cross-bar 53 the heads 52 will barely touch them.

The base 13 is mounted upon two or more hinged bars 54, operated by means of the 15 push-button 55, its rod 56, and bell-crank 57, journaled in the bracket 58, secured to the organ-housing. The rod 56 is provided with a catch 59, suitable to slip over the pin 60, in which position the base 13 and all the parts 20 connected therewith are ready for work.

The tappets 38 (shown in Fig. 5) are loosely screwed or otherwise movably fastened into the drum 26, and are provided with a broad 25 and a narrow wing. The narrow wing is of less depth than the broader wing in order to turn said tappets, notwithstanding the adjacent laths 37, against which the broad wing rests when struck by a pin 39 or a hook 40. The object in making the wings of different 30 widths is to allow the pin 39 to come into contact with the tappet when the broader part is turned one way and to miss it when turned the other way. If, however, the tappet 38 is turned in a direction opposite to that in 35 which it strikes the pin 39, the hook 40 will be struck by the broader wing of the tappet and the pin 39 can pass without being touched. By this simple arrangement the period during which a certain register is to remain open 40 can be regulated at will. If, for instance, a certain register has to be kept open for a given time in a combination intended to be played, the player sets a suitable number of tappets in such manner that the broad wings of said 45 tappets will come under the pin 39 of the oblong board connected by its rod 61 to the slide of that particular register. The first of said series of tappets will strike the pin 39 and tilt its oblong board, (see Fig. 1,) and as 50 thereby the pin 39 gets without the reach of the tappets belonging to the same series they cannot influence it any further. The hook 40 being missed by the narrow wings of the tappets will remain idle; but if it is desirable 55 to close the register the tappet following said series of tappets is set in such a manner that the hook 40 will be influenced and close the register by returning the oblong board 44 into its vertical position by means of the screw-head 52. If it is desirable to keep said board 60 in this vertical position, the broader wings of the tappets will be turned into the path of the hook 40 and it will be moved by each tappet, but cannot influence the board 44.

65 The shape of the tappet may be varied at will. The small wing may be omitted in order to economize space where a great number

of registers has to be operated, and consequently a great number of tappets must be placed upon the drum.

In operation the thumb-board 4 is pressed inward at the opportune moment, whereby the point of the bent lever 14 must turn the drum 26. By means of the illustrated connections the fork of the lever 31 must leave 70 its pin 32, but not before the cross-bar 62 of the lever 12 has forced itself between the pin above it and the next in order that the drum cannot execute an undesired motion. An extra security to the same end is aimed at by 80 providing the lever 23 with a tooth 24, so that the drum cannot by chance move forward or backward when such movement is not desirable. Whether few or many of the oblong boards are to be operated during a certain 85 partial rotation of the drum is decided by the combination of registers which the player intends to use. In order to arrange such combination before the play commences, the player lifts the button 55 and the base 13 and 90 the drum are lowered, whereby the contact between the upper tappets and oblong boards is broken and at the same time the tooth 24 and the point of the bent lever 14 are withdrawn from the ratchet 25, because in descending the free end of the double-armed lever 23 strikes the cross-bar 63 and its other arm is forced downward and compels the horizontal arm of the bent lever 14 to descend likewise as the hinged loop 64 does not allow 95 said bent lever to remain in its former position when the toothed arm of lever 23 is compelled to descend. The hinged levers 41 are prevented from moving too far back by means of the adjusting-screws 65 in the cross-bar 47. 100 If the combination of registers has been set, the tappets 38 must retain their position on account of the springs 66 pressing against their broad wings, and by pushing back the button 55 all parts are brought into a working 105 position and will respond to the call of the player as soon as he touches the thumb-board 4.

It is evident that the arrangement and shape of the several parts may be altered at will 110 without departing from the spirit of my invention.

It is a matter of importance to have the drum 26 and the oblong boards 44 always in full view during the play and to be able to close, if necessary, a register earlier than originally intended by simply tilting the identical oblong board back in its vertical position by the pressure of the hand before its lever 41 can accomplish it. The boards may 120 be provided with letters or signs indicating the registers with which they are connected. Likewise the different rows of tappets may be numbered or marked in any desirable manner to aid the player in setting the tappets for any combination of registers.

I claim—

1. In an organ the combination with a keyboard of a thumb-board, a drum, links and

levers for rotating said drum, a ratchet and pins for preventing chance motion of said drum, reversible tappets on said drum, means for operating the organ-registers through contact with said tappets comprising contact-pins on oblong boards pivotally suspended engaging said tappets when turned one way and hooked levers engaging them when turned the other way, and a rod and bell-crank to raise and lower the drum and the mechanism connected therewith.

2. In an organ the combination with a keyboard of a thumb-board pivotally connected with the organ-housing, a spring or springs to return said thumb-board to its original position, a vertically-movable base, a rod and bell-crank to cause said vertical motion of the base, a forked lever pivotally connected with said base, a link between said forked lever and the thumb-board, a bent lever pivotally attached to said link and held thereto by means of an eyebolt and spring, a post with an adjusting-screw to limit the motion of said bent lever, bearings on said base, a drum mounted in said bearings, a ratchet-wheel on said drum and pins upon the periphery of said drum contacting periodically with a cross-pin in said forked lever to limit partial revolution of said drum.

3. In an organ the combination with a keyboard of a thumb-board pivotally connected with the organ-housing, a vertically-movable base, a rod and a bell-crank to cause said vertical motion of the base, a forked lever pivotally attached to said base, a link between said forked lever and said thumb-board, a bent lever pivotally attached to said link, bearings on said base, a drum journaled therein, a ratchet on the end of said drum, a double-armed lever having a tooth, the end of said bent lever and said tooth engaging said ratchet, posts attached to said base, a slotted lever between said posts, said double-armed

lever being mounted in said slotted lever, another forked lever journaled in the spurs of 45 said posts, an adjustable rod between said forked levers, a leaf-spring attached to said base, an adjusting-screw in said slotted lever bearing against a fixed plate on said posts, and a spring for said double-armed lever. 50

4. In an organ the combination with a keyboard of a thumb-board, a movable base, a forked lever pivotally attached to said base, a link between said forked lever and said thumb-board, a bent lever on said link, an 55 adjustable contact for said bent lever, a spring or springs to return said thumb-board to its original position, another forked lever journaled in the spurs of the posts on the base, a slotted lever between said posts, a double- 60 armed lever carried by said slotted lever, bearings on said base, a drum journaled in said bearings, a ratchet on said drum, pins on the drum alternately in contact with said forked levers, reversible tappets on said drum 65 in contact with a pin in one position and in contact with a hook when in the other position, laths upon the circumference of said drum, pivotally-suspended oblong boards, a contact-pin on each of said oblong boards, a 70 hinged bar for each oblong board, a hook on the free end of each of said hinged bars, springs holding said boards alternately in a vertical or in a tilted position, rod connections between said oblong boards and registers, springs to retain said tappets when set, 75 a rod and a bell-crank to raise and lower said base, and a fixed contact for the outer arm of said double-armed lever having a tooth.

In testimony that I claim the foregoing as 80 my invention I have signed my name in presence of two subscribing witnesses.

CHRISTIAN STOLLEWERK.
